UNITED STATES PATENT OFFICE.

JAMES D. FOSTER AND JOHN L. RISON, OF HUNTSVILLE, ALABAMA.

DELIVERY-CABINET.

SPECIFICATION forming part of Letters Patent No. 548,534, dated October 22, 1895.

Application filed July 5, 1895. Serial No. 555,018. (No model.)

To all whom it may concern:

Be it known that we, JAMES D. FOSTER and JOHN L. RISON, citizens of the United States, residing at Huntsville, in the county of Madison and State of Alabama, have invented certain new and useful Improvements in Delivery-Cabinets; and we do hereby declare the following to be a full, clear, and exact description of the invention, such as will enable others skilled in the art to which it appertains to make and use the same.

Our invention relates to improvements in store-furniture articles of that class known as "delivery bins or cabinets," designed more especially for the purpose of storing and delivering powder and shot, although the cabinet may be used for storing other substances than those herein mentioned.

The objects that we have in view are, first, to provide a simple and inexpensive cabinet in which quantities of different substances can be stored until it is desired to withdraw a part or the whole of certain of the contents in any one of the compartments; second, to provide convenient means for conveying the substance from any one of the compartments to a central spout for directing the substance into a scale-pan; third, to provide a simple valve or gate mechanism for each compartment of the cabinet, and, finally, to provide a locking contrivance adapted to lock all the valves of the series of compartments when the valves are closed.

With these ends in view our invention consists in the combination of devices, and in the novel construction and arrangement of parts, which will be hereinafter fully described and claimed.

To enable others to understand our invention we have illustrated the preferred embodiment of our cabinet in the accompanying drawings, forming a part of this specification, in which—

Figure 1 is a front elevation of a cabinet constructed in accordance with our invention. Fig. 2 is a vertical transverse sectional view thereof on the plane indicated by the dotted line $\alpha\alpha$ of Fig. 1. Fig. 3 is a detail perspective view of one of the valves and its operating-stem. Fig. 4 is a detail view of the locking-bar.

Like letters of reference denote corresponding parts in all the figures of the drawings, referring to which—

A designates the inclosing shell or casing 55 of the cabinet. We prefer to make this casing of substantially rectangular shape, and to mount it upon the legs a , although the shape and the way of supporting the cabinet are not material and may be varied at pleasure. 60 This case A is divided into a series of compartments B C by means of the transverse partitions b b , and each compartment has a sloping false bottom c , which inclines downward toward and below a discharge-port d , 65 provided in the solid front rail a' of the cabinet. We prefer to provide a glass front e to the series of compartments to enable the store-keeper to readily ascertain the quantity of powder and shot or other substances contained in the compartments of the cabinet; 70 but the use of this glass front e is optional and may be omitted.

To the solid front rail a' of the cabinet is secured a metallic facing strip or strips F, 75 which may be fastened in place by screws or in any other suitable way, and in said facing-strip is provided a series of openings or notches f , which coincide with the series of discharge-ports d from the series of compartments B C. In the drawings we have shown two of these facing-strips with their contiguous ends spaced to provide an opening in line with the port d from the central compartment C; but it is evident that a single 85 continuous strip may be used with an opening or recess to coincide with the port of the compartment C.

G H designate the sloping conveyer troughs or chutes, and I is the central spout by which the contents of the several compartments B C may be conveniently discharged into a scale-pan or other receptacle. These chutes and the spout are suitably secured to the front rail a' of the cabinet below the series of ports 95 d from the compartments, and we prefer to arrange the spout I below the central compartment C, while the chutes G H are below the side compartments B B. The chutes are closed at their outer ends at the sides of the 100 cabinet, and said chutes are inclined or arranged in sloping positions from the sides of

the cabinet toward the central spout I, whereby the substances deposited into the chutes from either of the compartments B will be directed by the chutes into the central spout.

5 The ports *d* from the compartments B C are normally closed by the series of gates or valves J K, which are pivoted to the front rail *a'* of the cabinet and are adapted to fit between the facing-strip F and the front rail *a'* across and over the ports *d*. The valves J are arranged to close the ports *d* to the compartments B and are provided with vertically-disposed operating-stems *j*, while the valve K is arranged to close the port to the central compartment C and it has a horizontal operating-stem *k*.

In the cabinet shown and herein described as an embodiment of our invention we intend to use the central compartment C for the storage of powder, while the side compartments B are for storing shot of different sizes. Hence we arrange the stem for the valve of the powder-compartment C in a different position from the valve-stems of the side compartments, so that the storekeeper will not be so liable to make a mistake in vending powder for shot, or vice versa, as when all the stems are arranged in the same positions. Each valve J has two lugs *j' j''*, one extending horizontally and the other vertically beyond the edge of the valve-plate, and through the lateral lug *j'* is passed the pivot-pin or screw that fastens the valve to the front rail *a'*, while a pivot-pin passes through the vertical lug *j''* and the lower end of the valve-stem *j* to partially connect the valve and its stem together. These vertical valve-stems *j* are fitted and guided in notches *l*, formed in the front overhanging edge of the top of the casing A, and they are held in place by a strip *l'*, fastened to the cabinet top over the notches *l*, the protruding ends of the valve-stems having suitable pull-pieces for their convenient manipulation. Each vertical stem *j* is provided with a notch *m* near its upper end, and into these notches are adapted to take the lips *n* on the horizontal locking-bar N. This locking-bar is fitted beneath the overhanging front edge of the top of the casing, and it has a series of longitudinal slots *n'*, through which are passed the screws *n''*, that serve to connect the locking-bar to the top of the casing in a manner to permit said bar to have a limited sliding movement. Said locking-bar has a series of notches *p* cut in its outer edge, forming the shoulders or lips *n*, and at one end this bar N has a suitable pull-piece *o* for its convenient manipulation. The vertical stems *j* of the valves J are fitted in the notches *p* of the pull-bar, and when all of the valve-stems are lowered to close the valves J across the ports *d* of the compartments B the bar N can be pulled out to force the lips *n* into the notches *m*, thereby locking all the stems *j* and the valves J across the ports of the side compartments.

If desired, each valve-stem *j* may be pressed normally downward to keep the valve J closed across the port from the compartment B by means of the coiled spring Q, (shown by Fig. 1,) said spring having one end resting upon a pin, shoulder, or lug on the valve-stem and its other end bearing against the overhanging edge of the top of the cabinet or against the locking-rod N.

The valve K is pivoted at an intermediate point of its length to the front rail *a'* by the pin or screw *k'*, and the horizontal stem *k* of said valve is guided in a suitable fixed keeper *k''*, the free end of the valve-stem *k* having a suitable finger-piece, as shown.

It is intended that our cabinet shall be placed in a store-counter in convenient position to a scales, so that the contents of the compartments may be discharged directly into the scale-pan; but if it is not convenient to so place the cabinet a flexible tube may be connected to the spout in order that the substance may be easily directed to the scales.

If the storekeeper desires to sell a quantity of powder, the stem *k* is pulled to raise the valve K and permit the powder to flow from the compartment C, through the port *d*, into the spout I, and thence to the scale-pan, after which the stem *k* is shoved back to close the port of said compartment C. To withdraw shot from either of the compartments B the rod N is forced in to release its shoulders *n* from the notched valve-stems, the proper valve-stem is lifted to raise the valve, and the shot can now flow into the chute G or H, thence to the spout I, and thence to the scale-pan, after which the valve-stem is shoved down and the rod N pulled out to lock all of the vertical valve-stems.

If desired, a suitable locking contrivance may be provided for the horizontal stem *k* of the valve K.

We are aware that changes in the form and proportion of parts and in the details of construction of the devices herein shown and described as an embodiment of our invention can be made by a skilled mechanic without departing from the spirit or sacrificing the advantages of our invention; and we therefore reserve the right to make such changes and alterations as fairly fall within the scope of our invention.

Having thus fully described our invention, what we claim as new, and desire to secure by Letters Patent, is—

1. The combination of a casing having a series of isolated compartments and with vertical guides, a series of gates across the discharge ports from said compartments, the valve stems connected to the gates and fitted in the vertical guides, and a locking rod slidably supported on the casing and having means adapted to engage with, or be disengaged from, the series of the valve stems, substantially as described.

2. A delivery cabinet comprising a casing divided into a series of isolated compartments and having the discharge ports and the vertical guides, the central spout, the reversely-inclined chutes, arranged below the ports, to deliver to the spout, the pivoted gates, the vertical valve stems fitted in the vertical guides and connected to certain of the gates, a locking rod common to all of said vertical stems and adapted to be engaged therewith, and to be disengaged therefrom, simultane-

ously and a horizontal stem connected to another of the series of gates, substantially as described.

In testimony whereof we affix our signatures in presence of two witnesses.

JAMES D. FOSTER.
JOHN L. RISON.
